DISPLAY STAND

Hubert S. Morgan, New York, N. Y., assignor to
 Beech-Nut Packing Company, Canajoharie,
 N. Y., a corporation of New York

Application July 26, 1938, Serial No. 221,295

1 Claim. (Cl. 211—128)

The present invention relates to display stands that are particularly adapted for displaying small articles such as five cent boxes and other packages of chewing gum, fruit drops and other confections.

5 The principal object of the invention is to provide a display stand of the character indicated which is of simple, strong and durable construction, which is capable of attractively displaying a large number and variety of articles to the best advantage, and which is convenient in use.

10 The preferred form of the invention is illustrated, by way of example, in the accompanying drawings, in which:

15 Figure 1 is a front view of the stand;

Fig. 2 is a longitudinal sectional view taken substantially on the line 2—2 of Fig. 1;

20 Figs. 3 and 4 are transverse sectional views respectively taken on the lines 3—3 and 4—4 of Fig. 1; and

25 Figs. 5 and 6 are detail views in perspective of preferred forms of article containing trays which may be used in connection with my improved stand.

30 My improved display stand as illustrated in the drawings is provided with vertical side walls 2 which may be suitably connected as by a frame member 4 at their lower rear corners and by a front wall 8.

35 A plurality of shelves 10 extend between the side walls and are secured thereto. The lowermost shelf has its forward end spaced a distance below the upper edge of the front wall 8 of the stand. This shelf is inclined upwardly and rearwardly as shown with its rear end spaced a distance from the rear edges of the side walls.

40 The next shelf is spaced a distance above the lowermost shelf and is also inclined upwardly and rearwardly. As shown, however, this shelf is inclined at a slightly less angle than the lowermost shelf.

45 The next shelf 10 is spaced above the underlying shelf and is inclined upwardly and rearwardly, but is shown at a slightly less angle than said underlying shelf.

Above this shelf is a fourth shelf which is spaced therefrom and is inclined upwardly and rearwardly but at a lesser angle.

50 The top shelf 10 may be inclined like the fourth shelf.

The forward edges of each of the second, third and fourth shelves above the lowermost one is spaced a distance below the upper edge of a rail 12 which is arranged at a slight angle to

the vertical and has its ends secured to the side walls. The foremost rail 12 is spaced a distance to the rear of the front wall 8, and the two other rails 12 are similarly spaced rearwardly. The front edge of each of the side walls is stepped and the rails 12 are secured to the vertical edges of these stepped portions. The rear ends of the shelves are successively spaced at the rear of each other.

5 As illustrated the third and fourth shelves may be provided with longitudinally extending partitions 14 which are spaced apart.

The space between adjacent partitions 14 is adapted to receive a tray 18. Each tray is made in the form of a chute having a bottom wall 20, upstanding flanges 22 on its longitudinal edges, upstanding corner flanges 24 on its forward edge, and a downwardly turned flange 26 on its rear end which may serve as a handle. Each tray may be provided with semi-annual upstanding ribs 28 formed therein that are spaced from the longitudinal edges thereof.

10 Each individual tray 18 may be filled with five cent boxes or other packages of chewing gum or candies and the like, with corresponding packages positioned in each tray one behind the other. The packages should be of a length corresponding to the width of the space between the flanges so as to permit them to slide widthwise and be guided by the tray flanges. The 15 ribs 28 permit the packages to slide freely by gravity.

20 When a tray is thus filled, it may from the rear of the stand be placed on the shelf between the partitions 14 and slid down into position with its forward end against the upwardly projecting portion of the rail 12.

25 The two lower shelves are each shown without the longitudinally extending partitions 14. These shelves may be used to support trays 29 30 in which each individual tray may be divided by partitions 30 into separate tray sections of varying widths. These trays may slide one beside the other, no partition being necessary. These trays also may be removed and replaced from the 35 rear of the stand.

Five cent boxes and packages of chewing gum of different manufacturers are of different lengths. In the use of the stand, it is desirable that the trays 18 and the spaces between the partitions 30 of the trays 29 shall be of a width corresponding to the length of the particular package that is to be used in the tray. With applicant's display stand the various trays and sections may be made of such width as to ac- 40 45 50 55

commodate different length packages of varying manufacturers.

The lower edge of each rail 12 is positioned in proximity to the articles positioned in the next 5 underlying tray so that the customer can only remove articles from such trays that are in front of the rail. Also most of the articles in the first four trays are protected from dirt and dust by being covered by the overlying shelf and 10 depending rail 12, and substantially only the articles in front of the depending rail are visible from the front of the stand.

The uppermost shelf 10 is in the form of a shallow box having a bottom wall 32, a front 15 wall 34, and a rear wall 36. The rear portion of the top of this box-like shelf has a cover 38 that is hinged at its forward edge. Upon lifting the cover, articles may be placed in the shelf and permitted to roll down into position at the front 20 of the shelf.

The rails 12 and the wall 34 are provided with reflecting surfaces, which reflect the articles below them in such a way as to give the appearance of a mass display. The parts of the stand may 25 be easily cleaned.

The lowermost trays may be used for supporting flat boxes such as five cent boxes of candy-coated gum 31 and these boxes to properly slide by gravity may require a different in- 30 clination of the supporting shelf than other types of packages which may be supported on the upper shelves. In the case of the two upper shelves, very little inclination is required as these shelves are intended to support cylindrical 35 rolls of fruit drops 33 and the like which may readily roll by gravity downwardly when the foremost package is removed.

One advantage of this stand from a practical viewpoint is the fact that a storekeeper in re- 40 filling the trays, will naturally supply the articles at the rear of the tray when the tray is pulled rearwardly for refilling purposes. This insures

fresh articles being moved into position at the front of the tray where they may be removed by the customer, and thus ensures articles being removed before they become stale. This arrangement also permits the storekeeper to watch 5 the contents of the trays and conveniently refill from his position behind the counter.

As will be evident to those skilled in the art, my invention permits various modifications without departing from the spirit thereof or the scope 10 of the appended claim.

What I claim is:

In a display stand for articles such as small packages of chewing gum and candies, side walls, shelves extending between and rigidly secured 15 to the side walls and spaced apart one above the other with their forward edges spaced one behind the other from the front toward the rear of the stand, said shelves being inclined upwardly and rearwardly, the angles of inclination of 20 the shelves decreasing from bottom to top, a plurality of trays mounted side by side on each shelf and extending fore and aft thereof, each tray being of shallow depth and having longitudinal side walls and a front end wall, the tops 25 of the trays being open, said trays being adapted to be individually slid rearwardly on their respective shelves, each shelf having an upstanding member at its forward edge which serves as an abutment for the front end walls of the trays, each shelf having a depending member at its forward edge with the lower edge of said member spaced in proximity to the top of the trays 30 on the underlying shelf, whereby each shelf and associated depending member covers the articles 35 in the trays on the underlying shelf so that substantially only the articles in front of the depending member are visible from the front of the stand, at least one of said shelves having transverse partitions between pairs of which partitions 40 trays are adapted to be confined.

HUBERT S. MORGAN.
